UNITED STATES PATENT OFFICE.

PETER ELLIS, OF WELLINGTON, NEW ZEALAND.

ROTARY MOTOR.

No. 823,717.

Specification of Letters Patent.

Patented June 19, 1906.

Application filed April 19, 1906. Serial No. 312,632.

To all whom it may concern:

Be it known that I, PETER ELLIS, a subject of His Majesty the King of Great Britain and Ireland, residing at Kilbirnie, Wellington, in the Provincial District of Wellington, in the Colony of New Zealand, have invented certain new and useful Improvements in Rotary Motors, of which the following is a specification.

10 This invention provides a motor of simple construction operated by steam, compressed air, or other fluid-pressure.

The invention comprises a drum or boss around which cylinders are arranged radially. 15 Ports through the drum give communication between the interiors of the cylinders and passages in a spindle, hereinafter referred to. Pistons are fitted into the cylinders, which are open at their outer ends, so that the pistons may project therefrom. 20 Leakage of steam past the pistons is prevented by cutting circumferential grooves or by fitting piston-rings around the pistons. The drum, with its cylinders, is mounted upon a hollow 25 axle having steam and exhaust ports separated by a partition, the said ports communicating, respectively, with the ends of the hollow axle. A casing provided with a cap and having an internal radius greater than the distance from the center of the drum to the outer end of the cylinders surrounds the 30 drum and radial cylinders, with the exception of the central part of the said casing, which is left open. One face of the drum fits 35 against a collar upon the end of the hollow axle to prevent leakage of steam. For a similar reason at the other end of the drum a ferrule fits against the face of the drum, against which it is held by a spring, the ferrule and spring being held in position by a 40 socket fixed to the shaft. The outer periphery of the casing is shaped to suit the class of work to which the motor is to be applied. Thus the said periphery may be shaped as a 45 pulley to receive a belt and may be lagged with wood or other non-conductor of heat, or it may be flanged to run upon a rail or adapted for driving by frictional contact.

The motor is started by turning the 50 low axle through part of a circle, when the pistons on the side to which the steam-port is turned are forced from their cylinders and press against the interior periphery of the casing, while the cylinders on the opposite side of the boss are open to the exhaust-port.

The casing and cylinders, with their boss, revolve upon the hollow axle.

The steam may be led from the exhaust-port to a steam-port farther along the hollow axle and thence to a second motor, and so on to other motors until the expansion of the steam is exhausted.

The drawings illustrate the invention adapted to drive by friction.

Figure 1 is an elevation; Fig. 2, a plan of the motor. Fig. 3 is a part sectional elevation on line A B, Fig. 2. Fig. 4 is a plan of the boss; Fig. 5, a similar view when constructed as a compound motor. Fig. 6 shows a shaft of the motor, and Fig. 7 a shaft of a compound motor.

Referring to the drawings, the boss 1 is bored to form cylinders 2, 3, 4, 5, 6, and 7, branching radially from the center of the boss, which has a bore 8. Ports 9 provide communication between the bore 8 and the cylinders 2, 3, 4, 5, 6, and 7. Pistons 10, 11, 12, 13, 14, and 15 fit the cylinders and are adapted to project therefrom. The ends of the pistons are rounded, or they may be provided with friction-rollers. The boss is mounted upon a hollow axle 16, having a steam-port 17 and exhaust-port 18 separated by a partition 19, the port 17 communicating with the end 20 of the axle and the port 18 with the end 21.

A casing 22 has a cap secured by bolts or screws 23 and has an internal diameter greater than the diameter of the boss 1. The casing surrounds the boss 1 and has a hole 24 of large diameter.

The motor is started by turning the hollow axle 16 by means of its lever 25 through part of a circle, when the cylinders 4 and 5 (see Fig. 3) receive steam from the end 20 of the axle 16 and the pistons 12 and 13 are forced outward and press against the interior periphery of the casing 22, while the cylinders 7, 2, and 3 are open to the exhaust end 21 of the axle 16.

The motor revolves the pulley 26, which has bearings 27 and 28, adjustable laterally by screws 29.

Leakage of steam between the axle and the drum is prevented by collars 30 and 31, integral with the axle and which receive ferrules 32 and 33, respectively, fitting against the faces of the drum and held thereagainst by the spring 34, fitting within the collars behind the ferrules. Steam leaking as aforesaid

finds access to the back of the ferrules, which are forced against the drum and make a steam-tight joint therewith.

What I claim, and desire to secure by Letters Patent of the United States, is—

1. A motor comprising in combination, a drum having a series of radially-formed cylinders, pistons for each of said cylinders, a casing of larger circumference receiving said drum and supported only by said pistons and an axle upon which the drum is revolvably mounted, said axle having motive-fluid and exhaust passages, each cylinder having a port giving communication with said motive-fluid and exhaust passages in the spindle alternately substantially as specified and illustrated.
2. A motor comprising in combination, a drum having a series of radially-formed cylinders, pistons for each of said cylinders, a loose casing of larger circumference than and receiving said drum and supported only by said pistons and an axle upon which the drum is revolvably mounted, said axle having motive-fluid and exhaust passages, each cylinder

der having a port giving communication with said motive-fluid and exhaust passages in the spindle alternately, and a pulley in adjustable contact with the periphery of said casing and affording an abutment to cause the drum and casing to revolve, substantially as herein specified and illustrated.

3. In a motor of the type indicated, a drum having a series of radial cylinders fitted with pistons, a loose casing larger than and receiving said drum and supported only on said pistons, a spindle upon which said drum is mounted having passages for the admission and exhaust of motive fluid from said cylinders, the drum and the casing revolving in the same direction substantially as herein specified and illustrated.

In testimony whereof I have signed my name to this specification in the presence of two witnesses.

PETER ELLIS.
